Primary Examiner — T Chase Nelson*Assistant Examiner* — Kelly L Gross(74) *Attorney, Agent, or Firm* — All West Law Group PLLC; Aaron Powell(57) **CLAIM**

The ornamental design for a soft spa, as shown and described.

DESCRIPTION

FIG. 1 is a top, right side perspective view of a soft spa, showing our new design;

FIG. 2 is a bottom, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 1; and,

FIG. 10 is an enlarged view of the portion 10 in FIG. 2.

The evenly dotted broken lines illustrate portions of the soft spa and form no part of the claimed design. The unevenly dashed broken lines define the boundaries of enlarged views and form no part of the claimed design.
